ABSTRACT

A photosensitive member is composed of an electrode layer, a photoconductive layer responsive to visible light and an ultraviolet photoconductive, electrically insulating layer. The photoconductive layer is irradiated by visible light from an object to be reproduced simultaneously with the negative corona charging of the electrically insulating layer to form an electrostatic latent image on the latter. At the same time, a positive voltage is applied to the electrode layer. The application of this voltage can also be accomplished during dry development of the image.

ELECTROPHOTOGRAPHIC SYSTEM

BACKGROUND OF THE INVENTION

This invention relates to electrophotographic systems employing electrophotographic sheet-shaped members including a photoconductive layer and the photoconductive, electrically insulating layer formed into a laminated structure and particularly to improvements in contrast of an image recorded on such a photosensitive member.

There are well known electrophotographic sheet-like members for use in electrophotographic processes, comprising a combination of a photoconductive layer and a thin layer of electrically high insulating material adapted to form a sustained electrostatic latent image on the insulating layer through the utilization of the effect of dielectric polarization on the high insulating and photoconductive layers.

This type of photosensitive member to sustain the desired image on the thin transparent layer of electrically high insulating material disposed on the surface thereof and therefore, unlike the well known Carlson process, the photoconductive layer thereof is not required to have the property that the residual electrostatic image is erased through discharge due to the irradiation of the layer with light after the electrostatic image has been latently formed, developed and recorded on the surface of the photoconductive layer. This has resulted in a great advantage in that the photoconductive layer can be increased in photosensitivity by using a material which is highly photosensitive and has a low resistivity such as for example, cadmium sulfide (CdS) or a selenium; tellurium (Se-Te) compound.

On the other hand, problems in the use of such a photosensitive member have been encountered in erasing any residual electrostatic image on the insulating layer after the image has been developed and recorded thereon and before the succeeding operation of forming another electrostatic latent image on that layer. If an electrostatic latent image is formed on the photosensitive member having residual electrostatic image this leads to a great objection since the latent image is developed in overlapped relationship with the preceding image on the member. Therefore it is essential to erase the residual charged image.

To this end, it is first required to strongly electrify the surface of the high insulating layer with an electric charge having a reverse polarity from that of the desired electrostatic latent image subsequently formed on the insulating layer. This has resulted in a disadvantage because a pair of positive and negative voltage sources, as high as several thousand volts must be provided for a corona charging device such as used in this context. One approach to the problems of eliminating this disadvantage is described and claimed in copending U.S. application Ser. No. 305,827 entitled "Electrophotographic Apparatus Using Photosensitive Member with Electrically High Insulating Layer," filed on Nov. 13, 1972 by the same applicants and assigned to the same assignee as the present application. According to the cited U.S. application a photosensitive member includes a visible photoconductive layer having superposed thereon a thin layer of electrically high insulating material transmissive to visible light and photoconductive in the ultraviolet range. The insulating layer is irradiated with visible light from an object to be reproduced and is simultaneously charged a predetermined

5 polarity by the discharge of a corona charging device to form an electrostatic latent image corresponding in pattern to the object on the insulating layer. After the electrostatic image, undeveloped or developed, has been transferred to a record medium, the electrostatic image left on the insulating layer is erased by irradiation with ultraviolet radiation. It has been found that, as the photoconductive layer has a finite dark resistance, a leakage current flows through that layer to 10 more or less charge the insulating layer with the same polarity as the bright portion of the electrostatic image. This leads to a decrease in the ratio of a concentration of the recorded image on the record medium to a concentration of the background on the medium. As a result, 15 the intensity of the recorded image decreases due to the decrease in this so called signal-to-noise ratio.

SUMMARY OF THE INVENTION

Accordingly, it is an object of the present invention to provide a new electrophotographic system utilizing a unique process which is highly efficient and has improved performance.

It is another object of the present invention to provide a new electrophotographic system for forming recorded images having improved signal-to-noise ratios.

It is still another object of the present invention to provide a new electrophotographic system for forming recorded images having both improved signal-to-noise ratios and improved contrast.

It is further object of the present invention to provide a new electrophotographic apparatus which accomplishes the objects described in the preceding paragraphs with a relatively simple structure.

It is an additional object of the present invention to provide a new and improved electrophotographic system which is less subject to troubles such as erroneous irradiation with light and leaks.

40 The present invention accomplishes these objects by the provision of an electrophotographic system comprising, in combination, a combined substrate and electrode member, a photoconductive layer, and an ultraviolet photoconductive, electrically high insulating layer disposed in the named order to form an electrophotographic sheet-like member, means for irradiating the photosensitive member with visible light from an object to be reproduced and simultaneously charging the insulating layer a predetermined polarity to form an electrostatic latent image corresponding in pattern to the object thereon, and means for developing the electrostatic latent image and fixing the developed image. The present invention is further characterized in that there is provided means for applying to the combined substrate and electrode member a biasing voltage having a reverse polarity from the above note predetermined polarity during the simultaneous irradiation-with-light and charging.

60 Preferably, a biasing voltage having its polarity reversed from the predetermined polarity may be additionally applied to the combined substrate and electrode member during the development of the electrostatic latent image.

65 Conveniently, the biasing voltage applied to the combined substrate and electrode member during the simultaneous irradiation-with-light and charging may be derived from the same biasing source as that applied to

the member during the development of the electrostatic latent image.

BRIEF DESCRIPTION OF THE DRAWINGS

The present invention will become more readily apparent from the following detailed description taken in conjunction with the accompanying drawings, in which:

FIG. 1 is a fragmental cross sectional view of a photosensitive member disclosed in copending U.S. application Ser. No. 305,827 as above cited;

FIG. 2 is a schematic diagram useful in explaining the principles of the present invention;

FIG. 3 is a graph illustrating the relationship between a surface potential on the photoconductive, electrically high insulating layer shown in FIGS. 1 and 2 and a biasing potential applied to the electrode shown in FIGS. 1 and 2;

FIG. 4 is a front elevational-sectional view of one embodiment constructed in accordance with the electro-photographic system of the present invention; and

FIG. 5 is a schematic side elevational view as viewed in a direction parallel to the direction of rotation of the photosensitive drum shown in FIG. 4.

DESCRIPTION OF THE PREFERRED EMBODIMENTS

Referring now to FIG. 1 of the drawings, there is schematically illustrated a photosensitive sheet-like member. The photosensitive member is generally designated by the reference numeral 10 and comprises a combined substrate and electrode member 12, a photoconductive, layer 14 and a layer 16 of photoconductive, electrically high insulating material superposed on each other.

According to the teachings of the cited U.S. application Ser. No. 305,827, the photoconductive layer 14 is formed of a photoconductive material sensitive to the spectral range of visible radiation. For example, the layer 14 may be prepared by mixing a cadmium sulfide (CdS) powder having added thereto very small amounts of copper and chlorine with from 5 to 50 percent by volume of a binder selected from the group consisting of the vinyl, acrylic and cellulose systems. The material thus prepared is applied on the combined electrode and substrate member 12 in any suitable manner. The layer 16 is composed of any suitable transparent, electrically high insulating material having photoconductive property within the spectral range of ultraviolet radiation. An example of the material of the layer 16 is polyvinyl carbazole containing about 0.2% by weight of picric acid and dissolved into a solvent such as dioxan, tetrahydrofuran or the like. The solution thus prepared is applied to the photoconductive layer 14 as by coating to form the ultraviolet photoconductive, electrically insulating layer thereon.

Any object to be reproduced, such as a document or a drawing or the like, can be electrically imaged onto the photosensitive member merely by only the following two steps:

The first step is to irradiate the photosensitive member 10 or the photoconductive layer 14 with a visible light image of the object to be copied, while at the same time any suitable corona charging device is used to charge the member 10 a predetermined polarity. Portions of the photoconductive layer 14 differently decrease in internal impedance in response to bright and

dark portions of the visible light image. As a result, the insulating layer 16 has formed on the surface thereof an electrostatic latent image including portions charged respectively positively and negatively with respect to ground potential in accordance with the bright and dark portions of the light image.

After the electrostatic latent image on the photosensitive member 10 has been subject to dry development, transfer and fixation processes (well known in the art), 10 the second step is to irradiate the photoconductive, insulating layer 16 with suitably intense ultraviolet radiation to decrease the internal impedance of the layer 16. This results in the erasure of the entire electrostatic latent image remaining on the surface of the insulating layer 16 so that the photosensitive member 10 is ready for the succeeding visible irradiation step.

At the first step of forming an electrostatic latent image, those portions of the photoconductive layer 14 not irradiated with visible radiation have resistances whose magnitudes are finite rather than infinitely great and accordingly leakage currents flow therethrough. These flows of leakage current impart to the insulating layer 16 electric charges identical in polarity to those resulting from the bright portions of the light image although the magnitudes of the charges are small. This means that a corresponding image transferred to and recorded on a record medium has its concentration decreased with respect to a concentration of the background on the record medium. Therefore the recorded image has a decreased signal-to-noise ratio.

Now assuming that the insulating and photoconductive layers 16 and 14 respectively have equivalent capacitances of C_1 and C_2 respectively, a quantity of electricity q_{ld} charged on the dark portion of the insulating layer 16 can be expressed by

$$q_{ld} = C_1 C_2 / C_1 + C_2 V$$

where V is a voltage applied across the photosensitive member 10 from a corona discharging device involved. 40 Since the C_1 is very larger than the C_2 , the q_{ld} is Since the capacitance C_1 is a very much larger than the capacitance C_2 , q_{ld} is and the voltage V . This is

$$q_{ld} \approx C_2 V$$

(1)

On the other hand, a quantity of electricity q_{lb} charged on the bright portion of the insulating layer 16 can be expressed by

$$q_{lb} = C_1 V$$

(2)

This is because the photoconductive layer 14 decreases in resistance due to the irradiation with light so that the term C_2 is negligibly small.

If the difference between the quantities q_{lb} and q_{ld} is increased, then the contrast of the recorded image will be improved. The difference between the quantities of electricity is calculated by the relationship.

$$q_{lb} - q_{ld} = V(C_1 - C_2) = V(1 - C_2/C_1) \approx V$$

(3)

From the equation (3) it is seen that the contrast of the recorded image is approximately proportional to the corona voltage V . in close approximation.

The present invention is based on the equation (3).

The principles of the present invention will now be described in conjunction with FIG. 2. The arrangement illustrated comprises the photosensitive member 10 of FIG. 1 including the photoconductive layer 14 formed, by way of example, of an N type semiconductive material. The arrangement further comprises a negatively charging device generally designated by the reference numeral 20 and including a length of very thin metallic wire 22 and a pair of grounded electrodes 24 disposed in opposite relationship whereby the length of wire 22 is located centrally therebetween. The length of wire 22 is connected to a source 26 of negative corona voltage to be applied with a negative corona voltage a corona discharge occurs between the length of wire and the grounded electrodes 24. The corona discharge uniformly charges the surface of the insulating layer 16 with the negative polarity. The combined substrate and electrode member 12 is connected to ground through a source 28 of biasing voltage unlike what is disclosed in the cited U.S. application. The source 28 applies a biasing voltage V_b to the electrode member 12.

To demonstrate the effect of the biasing voltage, FIG. 3 illustrates a surface potential V_s on the insulating layer 16 in ordinate plotted against the biasing voltage V_b in abscissa with the potential and voltage expressed in volts.

In FIG. 3 a solid line *a* describes surface potential on the insulating layer 16 after the layer has been negatively charged by the charging device 20 without irradiation by visible radiation. Another solid line *b* describes a surface potential on a similarly charged portion of the insulating layer 16 which has been irradiated by visible light on the order of 30 luxes. Thus the solid line *a* can represent a surface potential on that portion of the insulating layer 16 corresponding to a dark portion of a visible light image of an object to be reproduced while the solid line *b* can represent a surface potential on that portion of the insulating layer 16 corresponding to a bright portion of the light image.

If the insulating layer 16 is subject to simultaneous exposure and negative charging with no biasing voltage applied to the electrode member 12 then the bright and dark portion of the insulating layer 16 are at surface potentials as shown at points B and A in FIG. 3 respectively. A difference between the surface potentials on the bright and dark portions of the insulating layer 16 is called a "contrast voltage" and designated by ΔV hereinafter. As seen in FIG. 3, contrast voltage is at most about 200 volts for a null biasing voltage. However the contrast voltage is increased through the negative charging, in the presence of the biasing voltage according to the principles of the present invention. For example, when a biasing voltage V_b of +350 volts corresponding to points B and B' as shown in FIG. 3 is applied to the electrode member 12, the resulting contrast voltage ΔV is of 370 volts; about 1.85 times greater than that for a null biasing voltage.

Also from FIG. 3 it can be seen that the biasing voltage exceeds a certain magnitude such as +500 volts corresponding to points C and C' shown in FIG. 3, the surface potential on the insulating layer 16 has a positive magnitude on the dark portion thereof and a negative magnitude on the bright portion thereof. The development of an electrostatic latent image is generally accomplished by applying toner particles charged with the positive or negative polarity to electrostatic latent image. Thus the use of toner particles, for example pos-

itively charged, permits the particles to adhere only to the bright portions of the insulating layer maintained at negative potentials. Consequently the present invention substantially eliminates the disadvantage of the cited U.S. application in which bright and dark portions of the insulating layer are charged with the same polarity in effecting the dry development and transfer with toner particles.

Therefore it will be appreciated that the present invention exhibits two results; the contrast voltage increases and a recorded image obtained by the dry development has an improved signal-to-noise ratio.

Referring now to FIG. 4, there is illustrated one embodiment of the present invention as viewed in a direction perpendicular to the axis of rotation of a rotary photosensitive drum. The arrangement illustrated includes a rotary photosensitive drum in the form of a hollow cylinder generally designated by the reference numeral 10. The drum 10 has a cylindrical surface including an inner electrode layer 12, an intermediate photoconductive layer 14 and an outer insulating layer 16 corresponding to the components 12, 14 and 16 shown in FIG. 1. The electrode layer 12 includes a plurality of electrode segments 12a, 12b, . . . 12n extending longitudinally of the drum 10 with predetermined longitudinal gaps formed therebetween. The photoconductive and insulating layers 14 and 16 respectively can be successively formed on the electrode layer 12, as above described in conjunction with FIG. 1 to complete the photosensitive drum 10.

If the gaps between the adjacent electrode segments are too broad, those portions of the photosensitive layer 14 disposed on the gap have formed thereon no electrostatic latent image resulting in the formation of a recorded image includes stripe-shaped blurs. This leads to a decrease in the quality of the recorded image. On the contrary, if the gaps are too narrow then those portions of the photoconductive layer 14 located above the gaps decrease in resistance and accordingly the electrode layer 12 fails to function as a segmented electrode.

Therefore the gaps between the electrode segments must be selected to be a width such that the quality of the recorded image is prevented from appreciably decreasing while the electrode layer is enabled to function as a segmented electrode. The optimum width of the gaps depends upon the required quality of the recorded image, the resistivity and thickness of the photoconductive layer 12 etc. It has been found that, with satisfactory results, the gaps are preferably in the order of from 30 to 150 microns with the photoconductive layer 14 formed by applying a cadmium sulfide powder mixed with from 5 to 50% by volume of an organic resin such as acrylic resin in a thickness of about 100 microns to the electric layer 12.

By forming the gaps as above described in the electrode layer 12, it is possible to apply a biasing voltage V_b to the electrode layer 12 and therefore to the photosensitive drum 10 only during the simultaneous irradiation-with-light and charging and during the development. This eliminates the danger of electric shocks and leakages and also decreases the chance of troubles as compared with the arrangement of FIG. 2 wherein, the entire area of the electrode member is biased with a high voltage.

For particular applications wherein the size of characters and/or the spacing therebetween are predeter-

mined, the gap may be approximately equal to the spacing between the characters, that may amount to several millimeters. In other words, the gap can be suitably determined for the particular application.

Another factor in determining the gap which is a dielectric breakdown voltage between the adjacent electrode segments 12a, 12b, . . . 12n. If desired, the adjacent electrode segments may electrically floated from the ground potential. Alternatively, in order to prevent an electric discharge across each pair of adjacent electrode segments, the latter may be applied with graded potentials. For example, if a potential of 1,000 volts is applied to the electrodes segment 12c, potentials of 500 volts may be applied to the adjacent electrode segments 12b and 12d while the electrode segments 12a and 12e (not shown) may be at a null potential.

As shown in FIG. 4, a visible light image of an object to be reproduced is focussed on the photoconductive layer 14 of the rotating drum 10 by a lens 32 before it has been transmitted through a negative corona discharging device 20 substantially transmissive to a visible light beam from the object 30. Simultaneously the device 20 negatively charges the insulating layer 16 of the rotating drum 10 and a brush 34a connected to a biasing source 28 engages only that electrode segment such as the electrode segment 12a overlain by the negatively charge portion of the insulating layer 16. Thus a positive biasing voltage from the source 28 is applied to that electrode segment 12a.

Under these circumstances, the negative corona voltage and the positive biasing voltage are applied in superposed relationship across the photosensitive drum 10 to form on the insulating layer 16 an electrostatic latent image corresponding in pattern to the object 30 with the contrast thereof improved due to an increase in the V in the equation (3) by the voltage V_b .

As the photosensitive drum 10 is rotated in the direction of the arrow shown in FIGS. 4, the biasing voltage V_b goes to zero and thereafter that portion having formed thereon the electrostatic latent image enters a dry development unit 36. In the development unit 13 selected ones of the electrode segments 12a, 12b, . . . 12n are again supplied the biasing voltages V_b from the source 20 by having brushes 34b contacted thereby while the latent image is developed with toner particles disposed therein in the well known manner. Preferably the biasing voltage V_b has a magnitude preselected so as to meet the requirements that a surface potential on the insulating layer 16 is positive or null on the portions thereof corresponding to the dark portion of the light image and negative on that the portions corresponding to the bright portion. This measure is particularly effective for preventing the insulating layer 16 from being somewhat charged resulting from a leakage current flowing through the photoconductive layer and also decreasing a concentration of the background on the associated record medium as previously described. Therefore the resulting recorded image has a much improved signal-to-noise ratio.

The development unit 36 is shown in FIG. 4 as including a grounded electrode 38 disposed in opposite relationship with the photosensitive drum 10. The grounded electrode 38 serves to effectively apply the biasing voltage V_b to the insulating layer 16. If desired, the electrode 38 may be supplied with a voltage suitable for the development of the latent image.

In the arrangement of FIG. 4, only a single electrode segment such as shown at 12a is supplied with the biasing voltage V_b from the source 20. However the present invention is not restricted to the application of the biasing voltage to the single electrode segment. If desired, the biasing voltage V_b may be simultaneously applied to a plurality of adjacent electrode segments whose circumferential length is somewhat longer than the effective charging width provided by the corona charging device 20 with the width of the brush 34a correspondingly widened.

While the biasing source 28 is utilized in common with the simultaneous irradiation-with-light and negative charging and the development, it is to be understood that a separate biasing source may be additionally provided for the development phase. Alternatively, the biasing voltage may continue to be applied to the electrode segments for a time interval extending from the simultaneous irradiation-with-light and negative charging to the development step.

The drum 10 with the developed image is moved past an ultraviolet lamp 40a serving to decrease the resistance of the photoconductive high insulating layer 16 to thereby erase the electrostatic image left thereon. At that time, the biasing voltage is not applied to the associated electrode segments and therefore the surface potential on the drum 10 becomes substantially null.

Then the rotating drum 10 reaches a transfer section including a supply roll 40 and a transferring roll 44.

30 The transferring roll 44 is operated to transfer the developed image from the drum to a dielectric coated tape from the supply roll 42 in the manner well known in the art.

35 Subsequently, the tape with the transferred image enters a fixation unit 48 where it is fixed by heating after which a cutter 50 cuts the tape to a predetermined length. At that time, the reproduction of the object has been completed.

40 On the other hand, during a further rotational movement of the drum 10 the photosensitive layer thereof is successively irradiated by a ultraviolet lamp 40b so that any residual electrostatic image is completely erased. Then the drum 10 is cleaned by a cleaning unit 52. Thus the photosensitive drum 10 is ready for a succeeding operation.

FIG. 5 shows the photosensitive drum 10 as viewed in a direction parallel to the axis of rotation thereof. As shown in FIG. 5, the drum 10 has one side on which the photoconductive and insulating layers 14 and 16 respectively are not disposed in order to expose the end portions of the electrode segments 12a, 12b, 12c, . . . Then the brushes 34a and 34b are arranged to be directly contacted by those end portions of the electrode segments.

55 The brush may be a sliding brush formed of an electrically conductive material, for example, a metal or carbon such as found in conventional electric motors, in order to diminish the wear of the electrode segments, a roller type electrode formed of an electrically conductive rubber or a metal may selectively contact the electrode segments.

60 In the arrangement of FIG. 4, the circumferential dimension or width of the electrode segments has been selected to range from the effective circumferential dimension or width of a light beam to about three times of the effective charging width provided by the negative corona charging device although it is not particu-

larly restricted. Since the conditions under which the light beam from the object irradiates the photosensitive drum is predetermined, a change in width of the electrode segments permits a variation in the quantity of charge on the insulating layer of the drum, resulting in a wide variety of controls of the electrophotographic recording characteristics and particularly of the charging characteristics. It has been also found that the gaps between the adjacent electrode segments are preferably tilted at angles formed between the direction of rotational axis of the drum and the direction of the diagonal of the corona charging device. However only for purposes of illustration, the gaps have been described as extending perpendicularly to the direction of rotation of the drum.

In summary, the present invention provides an electrophotographic system in which simultaneous irradiation-with-light and charging and the development is effected while the electrode involved is provided with a voltage having a polarity reversed from that of the charging voltage. This causes not only an increase in contrast voltage but also an improvement in the signal-to-noise ratio during development.

While the present invention has been described in conjunction with a few preferred embodiments thereof it is to be understood that numerous changes and modification may be resorted to without departing from the spirit and scope of the invention. For example, instead of the electrode segments disposed on the cylindrical surface, sectional electrodes may be disposed on one end side of the photosensitive drum. Also the photoconductive layer may be formed of a P type semiconductive material in place of an N type material with the polarity of the charging and biasing voltage accordingly varied. For example, selenium or selenium-tellurium compound of P type conductivity may be used to form the photoconductive layer.

What we claim is:

1. An electrophotographic system comprising, in

combination, a photosensitive member comprised of a combined substrate and electrode layer, a photoconductive layer and an ultraviolet photoconductive, electrically high insulating layer disposed in the recited order to form an electrophotograph sheet-like member, means operatively positioned for irradiating said photosensitive member with visible light from an object to be reproduced and simultaneously charging said insulating layer with a predetermined polarity to form an electrostatic latent image corresponding in pattern to the object thereon, and means operatively positioned for developing and fixing the electrostatic latent image, wherein means are provided for applying to said combined substrate and electrode layer a biasing voltage having its polarity reversed from said predetermined polarity simultaneously with the irradiation-with-visible light and charging.

2. An electrophotographic system as claimed in claim 1, wherein a biasing voltage having its polarity reversed from said predetermined polarity is further applied to said combined substrate and electrode layer during the development of the electrostatic latent image.

3. An electrophotographic system as claimed in claim 2, wherein said biasing voltage applied to said combined substrate and electrode layer during the simultaneous irradiation-with-light and charging is derived from the same biasing source as that applied to said member during the development of the electrostatic latent image.

4. An electrophotographic system as claimed in claim 1, wherein said combined substrate and electrode layer is formed of a plurality of electrode segments disposed to form predetermined spacings therebetween.

5. An electrophotographic system as claimed in claim 2, wherein said combined substrate and electrode layer is formed of a plurality of electrode segments disposed to form predetermined spacings therebetween.
